UNITED STATES PATENT OFFICE.

RASMUS N. JENSEN, OF SALT LAKE CITY, UTAH.

WALL BOARD.

Application filed October 19, 1925. Serial No. 63,302.

My invention relates to building material, and has for its object to provide a new and useful reenforced wall board which may be made up into many widths and lengths, and which may be rolled up for transportation and handling.

These objects I accomplish with the manufactured article illustrated in the accompanying drawings in which similar letters and numerals of reference indicate like parts throughout the several views, and described in the specification forming a part of this application and pointed out in the appended claim.

In the drawings in which I have shown the best and most substantial embodiment of my invention, Figure 1 is a plan view of the sheet of the manufactured article, with parts cut away to show the reinforcement sheet of the board. Figure 2 is an end elevation of the same. Figure 3 is an end view of some of the wall board rolled into compact form.

In the drawings I have shown a piece or section of the wall board, as A, and which is made up of parallel strips B. The said strips B are held in spaced relation to each other by the reenforcing element C which is made of intermeshing or woven wire, and is medially and longitudinally embedded in the said strips B joining said strips into a sheet and with as many of the strips as desired. The edges of the strips are beveled on each side, as at 1. The said strips B are made of any plastic material which will set quickly, such as hydraulic cement, plaster, or papier-mâché, preferably of keen cement or hard wall plaster.

In using my wall board on the interior or exterior wall of a building one of said strips B is horizontally nailed to the studding or other frame portion of the building, and by driving small nails, such as lath nails through the strips as desired to hold the sheet in place or by driving the nails through the exposed portions of the reinforcing element. The said wall board may then be covered on one face or side with a coating of plaster or other wall material such as stucco or cement plaster to fill the grooves between the strips. In handling and shipping my wall board the sections of the board may be rolled, as the wire is fine enough to bend readily where not covered with the set plastic material, and the reinforcing wire then acts as a hinge connecting the adjacent strips B, and the beveled edges of the strips allow such rolling without injuring the board. The sections or sheets of board may be easily cut to fill all small wall spaces, or to patch plastered walls.

Having thus described my invention I desire to secure by Letters Patent and claim:

A flexible wall board consisting of a flexible sheet of perforated reenforcing material, a plurality of bars of plaster board material formed on the flexible sheet in spaced relation to each other to leave portions of the sheet completely exposed, the bars having their adjacent edges beveled at both sides of the sheet.

In testimony whereof I have affixed my signature.

RASMUS N. JENSEN.
